(57) **CLAIM**

The ornamental design for a handle for a Richardson style surgical retractor, as shown and described.

DESCRIPTION

FIG. 1 is a front perspective view of a first embodiment of a handle for a Richardson style surgical retractor showing our new design;

FIG. 2 is a rear perspective view thereof;

FIG. 3 is a left side elevational view thereof;

FIG. 4 is right side elevational view thereof;

FIG. 5 is a rear elevational view thereof;

FIG. 6 is a front elevational view thereof;

FIG. 7 is a top plan view thereof;

FIG. 8 is a bottom plan view thereof;

FIG. 9 is a front perspective view of a second embodiment of FIG. 1, the only difference being that the inner central channel is not included, it being understood that all other surfaces are the same as those of the first embodiment;

FIG. 10 is a rear perspective view of the embodiment in FIG. 9;

FIG. 11 is a top plan view of the embodiment in FIG. 9; and, FIG. 12 is a right side elevational view of the embodiment in FIG. 9.

The broken lines shown in the drawings are included for illustrating portions of the handle for a Richardson style surgical retractor that form no part of the embodiment in which they are shown. The dash-dot-dash broken lines represent the bounds of the embodiment in which they are shown and form no part thereof.
